PORATABLE SET OF ORCHESTRA BELLS OR SIMILAR ARTICLE

Clair O. Musser, Studio City, Calif., assignor to CBS
Musical Instruments, a division of Columbia Broad-
casting Systems, Inc.

Filed Apr. 10, 1970, Ser. No. 22,372

Term of patent 14 years

Int. Cl. D17—04

U.S. Cl. D56—1

FIG. 1.

FIG. 2.

FIG. 3.

FIG. 4.

FIG. 5.

FIG. 6.

FIG. 1 is a front elevational view of a portable set of orchestra bells or similar article embodying the new design of my invention;

FIG. 2 is a rear elevational view thereof;

FIG. 3 is a top plan view thereof;

FIG. 4 is a bottom plan view thereof;

FIG. 5 is a side-elevational view showing one end thereof; and

FIG. 6 is a side-elevational view showing the other end thereof.

The essential features of my new design reside in the configuration of the base supporting the bars.

I claim:

The ornamental design for a portable set of orchestra bells or similar article, substantially as shown and de-
